[57] CLAIM

The ornamental design for a cable clamp, substantially as shown.

DESCRIPTION

FIG. 1 is a rear perspective view of a cable clamp showing my new design;

FIG. 2 is an enlarged right side elevational view thereof;

FIG. 3 is an enlarged top plan view thereof;

FIG. 4 is an enlarged bottom plan view thereof;

FIG. 5 is an enlarged front elevational view thereof;

FIG. 6 is an enlarged rear elevational view thereof;

FIG. 7 is an exploded rear perspective view thereof. The left side elevational view of the cable clamp is identical to the right side elevational view of FIG. 2.

FIG. 1

FIG. 5

FIG. 3

FIG. 2

FIG. 4

FIG. 6

FIG. 7
